UNITED STATES PATENT OFFICE.

HENRY JOHN STOFFELS, OF NORWOOD, OHIO.

GUIDE-FRAME FOR GAS-HOLDERS.

No. 901,205.

Specification of Letters Patent.

Patented Oct. 13, 1908.

Application filed January 15, 1908. Serial No. 410,905.

To all whom it may concern:

Be it known that I, HENRY JOHN STOFFELS, a citizen of the Empire of Germany, residing in Norwood, in the county of Hamilton and State of Ohio, have invented certain new and useful Improvements in Guide-Frames for Gas-Holders, of which the following is a specification.

This invention relates to an improved 10 guide-frame for gas-holders by which the stresses in the guide-frames of gas-holders when subjected to wind pressure are more effectively disposed of at opposite sides of the guide-frame, and thereby an easier motion 15 of the gas-holder obtained.

In the guide-frames heretofore in use the gas-holder is guided on the columns by means of rollers, which can be radial, or of a combined system of radial and tangential 20 rollers. The old radial roller-type has one radial roller which is guided along the inside-face of the guide-column. The combined radial and tangential roller-type has an inside radial roller and two tangential 25 rollers. The consequence will be that when the gas-holder is acted on by wind pressure only the guide-columns on the leeward side are acted upon, while the columns on the windward side are not acted upon, so that 30 the distance between the gas-holder and guide-frame will be increased on the windward side and decreased on the leeward side. The radial guide-rollers will be in close contact with the guide-columns on the 35 leeward side, while they do not even touch them on the windward side. This is objectionable as it impedes the movement of the gas-holder in its guide-frame.

The object of this invention is to furnish 40 an improved construction of guide-frame for gas-holders in which all the columns are called into action, that is to say, in which all the guide-columns on the windward side as well as on the leeward side are called into 45 action, and thereby the motion of the gas-holder when the same is exposed to wind pressure facilitated and the stresses on the guide-frame reduced; and for this purpose the invention consists of a guide-frame for 50 gas-holders the columns of which are acted upon on one side by one radial roller supported on the gas-holder and on the opposite side by two radial rollers, the latter acting on the windward side of the guide-columns, 55 while the inside radial rollers act upon the leeward side of the guide-columns, as will

appear from the following description and claims.

In the accompanying drawings, Figure 1 is a horizontal diagrammatic section of my 60 improved construction of gas-holder and guide-columns with inside and outside radial rollers, when the gas-holder is subjected to wind pressure, Fig. 2 is a like horizontal section, showing the gas-holder and its 65 guide-columns subjected to wind pressure and arranged with inside and outside radial rollers and with tangential rollers according to my improved construction, and Figs. 3 and 4 are sectional plan-views of my 70 improved construction of gas-holder and guide-columns, drawn on a larger scale and showing the location of the radial guide-rollers of Figs. 3 and 4 respectively on the windward and on the leeward side of the gas- 75 holder.

Similar letters of reference indicate corresponding parts throughout the views.

Referring to the drawings, *a* represents a gas-holder and *b* the guide-frame for the 80 same, which latter consists of a number of upright guide-columns *b*¹ which are located at the circumference of the steel tank surrounding the gas-holder. The gas-holder *a* is provided with radial rollers *d*, the axes 85 of which are supported in radial supports *d*¹. The radial guide-rollers *d* are guided along the inside faces of the guide-columns on the up and down motion of the gas-holder. To the supports *d*¹ are applied two 90 additional rollers *e* *e*, one on each side of the webs of the guide-columns, which act on the outer faces of the guide-columns. As shown, the guide-columns are each composed of two I-beams placed at right angles to each other 95 and the inner radial rollers *d* cooperate with the faces of the inner flanges of the inner I-beams. The rollers *e* cooperate with the outer faces of said inner flanges at opposite sides of the web, thus acting oppositely to 100 the inner radial rollers, the axes of said rollers *e* extending parallel to those of the inner rollers.

Normally the gas-holder, when there is no wind pressure, is guided by the larger radial rollers *d* and the smaller pair of outside rollers *e* without any stress on the guide-columns. When the gas-holder is subjected to wind pressure, the radial guide-rollers at 105 the windward side are moved away from the faces of the guide-columns and at the leeward side towards the guide-columns so that 110

the radial guide-rollers leewards are placed in contact with the same. The radial guide-rollers *e* which are located at right angles to the wind are not called into action. The 5 pair of radial rollers on the windward side are placed in contact with the guide-columns and the pair of radial guide-rollers on the leeward side are moved slightly away from them so as not to be called into action, so 10 that the gas-holder is supported on the windward side by the smaller pair of guide-rollers and on the leeward side by the larger guide-rollers. By this arrangement the guide-columns that are located on the windward side are called into action as well as 15 those on the leeward side, while the two guide-columns which are located at right angles to the direction of the wind are not acted upon by the radial rollers.

20 The pair of radial guide-rollers can also be used in connection with the large radial guide-roller *d* acting on the inner face of the guide column and the two tangential rollers *f f* acting on the side-faces at the 25 outer ends of each guide-column, as shown in Fig. 2. These side-faces are formed by the flanges of the outer I-beam. The effect of this arrangement is that when the gas-holder is subjected to wind pressure the resultant of the tangential and radial forces 30 will be the same for each guide-column, the tangential rollers acting upon the columns at the sides which are not acted upon in the arrangement shown in Fig. 1. In this manner 35 all the columns will be brought into action and subjected to a uniform strain.

The advantage of the improved construction of guide-frame and inside and outside radial guide-rollers for gas-holders is that 40 by the decreased stresses exerted on the guide-columns a considerable saving in material is obtained, and also the easier and more reliable movement of the gas-holder when subjected to wind pressure.

45 Having thus described my invention, I claim as new and desire to secure by Letters Patent:

1. The combination, with a gas-holder and the guide-frame for the same composed of a

plurality of upright guide-columns, of radial 50 rollers moving over the inner face-sides of said guide-columns, and radial rollers moving over the outside of the guide-columns and acting oppositely to said first-named radial rollers. 55

2. The combination, with a gas-holder and the guide-frame for the same composed of a plurality of guide-columns, of radial rollers moving over the inner face-sides of the columns, tangential rollers moving over the 60 outer rear-ends of the columns, and radial rollers moving over the outsides of the columns and acting oppositely to said first-named radial rollers.

3. The combination, with a gas-holder and 65 a guide-column therefor having inner and outer guide-surfaces, of a roller on the gas-holder traveling on the inner guide-surface, and means on the gas-holder acting oppositely to said roller and coöperating with the 70 outer guide-surface.

4. The combination, with a gas-holder and a guide-column therefor comprising an I-beam, of a radial roller mounted on the gas-holder and traveling on the inner face of 75 one flange of said I-beam, and radial rollers on said gas-holder having their axes parallel to that of said first-named roller and traveling on the outer face of said flange at opposite sides of the web. 80

5. The combination, with a gas-holder and a guide-column therefor composed of inner and outer I-beams arranged at right angles to each other, of a radial roller on the gas-holder traveling on one of the flanges of the 85 inner I-beam, a pair of radial rollers on the gas-holder traveling on the opposite face of said flange at opposite sides of the web, and tangential rollers on the gas-holder traveling on the flanges of the outer I-beam. 90

In testimony, that I claim the foregoing as my invention, I have signed my name in presence of two subscribing witnesses.

HENRY JOHN STOFFELS.
